UNITED STATES PATENT OFFICE.

SIMON W. WARDWELL, JR., OF BOSTON, MASSACHUSETTS.

DESIGN FOR A COP.

SPECIFICATION forming part of Design No. 22,690, dated August 8, 1893.

Application filed February 29, 1892. Serial No. 423,285. Term of patent 14 years.

To all whom it may concern:

Be it known that I, SIMON W. WARDWELL, Jr., a citizen of the United States, residing at Boston, in the county of Suffolk and State of Massachusetts, have invented a certain new and useful Design for a Cop, of which the following is a specification.

The essential feature of my design consists in a cop or cylinder, the surface of which presents an ornamental appearance in the shape of ribbed sections, substantially as herein-after pointed out.

In the drawings, Figure 1 is a side view of a cop; and Fig. 2 is a similar view of the opposite side of a cop showing the design.

The surface of the cop shows a pattern embracing triangular portions or figures *a*, *b*, and side portions *c*, *c'* upon opposite sides of the triangular portions. One side of the cop shown in Fig. 1 presents a pattern embracing the triangular portions *a*, in which the ribs are arranged in two series, 1, 2, each series being parallel to one of the long sides of the figure or triangle and converging toward the line *x*, while in the triangular portions *b*, the ribs are shown in two series 3, 4, converging toward a central line *z* through the triangular portion, but at an angle to the long sides of the triangle. The apices of the triangular portions *a* and *b* are opposed to each other. The side portions *c*, *c'* present an appearance of two series of parallel ribs, each series being parallel with the long lines of the trian-

gular portions *b*, and extending so as to converge at the central longitudinal line *x* of the 35 triangles *a*. The ribs of the adjacent portions *c*, *c'* converge at a line *y*. The cop presents an appearance on the side shown in Fig. 2, of having a triangular portion *a*, presenting the appearance of two series of ribs, 1, 2 40 extending respectively parallel with the long sides of the triangular portion, and a triangular portion *b*, having two series of ribs 1, 2, converging toward a central, longitudinal line *z* through the triangle, the two triangles *a*, *b*, 45 having their apices opposed to each other and on either side of the triangles are side portions *c'* presenting the appearance of parallel ribs, but the ribs of the two sections are at an angle to each other. Outside of the side sections *c'* are the side sections *c* showing the parallel ribs at an angle to the adjacent rib sections *c'* converging at the line *y*, while the edges show right angle triangular sections of parallel ribs *a'*, *b'*. Both sides of the cop present the appearance of a spirally wound band or ribbon, as indicated by the lines *d*, *d'*, *d''*. 50 55

What I claim is—

A design for a cop, substantially as shown.

In testimony whereof I have signed my 60 name to this specification in the presence of two subscribing witnesses.

SIMON W. WARDWELL, JR.
